ATTORNEY

UNITED STATES PATENT OFFICE.

EDWARD G. PATTERSON, OF BISMARCK, NORTH DAKOTA.

COLLAR BUTTON.

Application filed October 1, 1923, Serial No. 665,968. Renewed January 20, 1926.

To all whom it may concern:

Be it known that I, EDWARD G. PATTERSON, a citizen of the United States, residing at Bismarck, in the county of Burleigh and 5 State of North Dakota, have invented new and useful Improvements in Collar Buttons, of which the following is a specification.

This invention relates to a collar button and has for its primary object the construction of a collar button that may be more easily arranged in place and when once in place will be positively held against accidental removal.

An object of the invention is the novel 15 manner of associating the parts so that they may be collapsed for insertion through the button hole and then easily extended for locking the button in place.

With these and other objects in view the 20 invention will be better understood from the following detailed description taken in connection with the accompanying drawing wherein:

Fig. 1 is a side elevation of one form of 25 button.

Fig. 2 is an enlarged detail view of the 30 cam head of the links.

Fig. 3 is a side elevation partly in section 35 of another form of my invention.

Again referring to the drawing illustrating two of the many constructions of my 40 invention and more particularly to Figs. 1 and 2 the numeral 1 designates a head that has projecting therefrom a pair of shanks 2 and 3 of a resilient metal so that the shanks may be sprung away from each other. A pair of links 4 and 5 are provided, each having cam shaped head 6 that is pivotally connected to a shank as indicated at 7. It will be noted these cam shaped heads act against each other for forcing the shanks 2 and 3 apart and this resilient action of the shanks 2 and 3 at the point of engagement between the cam heads will allow the

shanks 4 and 5 to move into extended position as illustrated in Fig. 1. Stops 8 on the shanks limit swinging movement of the links. Thus it will be seen that in a very simple manner links may be thrown parallel to each other for easy insertion through the hole of the collar and then quickly extended and locked against turning movement.

In Figure 3 I have shown the shank 9 provided with a hollow barrel 10 in which 55 is mounted the spring 11 acting against the collar 12 mounted on the bar 13 to the ends of which are attached the knobs 14 and 15. In this particular instance the knob 14 is forced towards the shank 9 so as to extend the 60 knob 15 to a position to be readily inserted through the hole of the collar. After the button has been inserted through the collar, knob 14 is released so that the spring may 65 extend the bar a distance to one side of the shank 9 equal to the length of the barrel 10.

It is of course, to be understood that the invention may be constructed in various other manners and the parts associated in different relations, therefore, I do not desire to be limited in any manner except as set forth in the claim hereunto appended.

Having thus described my invention what I claim is:

A collar button comprising a head, a pair 75 of normally parallel shanks projecting from one side of the head, a pair of retaining links pivotally connected to the outer ends of the shanks and adapted to project in longitudinal alignment therewith, or extended at right-angles thereto, cam shaped heads on the links at their pivot points for spreading the shanks when the links are moved to an extended position and stops on the shanks for limiting the swinging movement 80 of the links.

In testimony whereof I affix my signature.

EDWARD G. PATTERSON.
